UNITED STATES PATENT OFFICE.

WINFIELD H. YOST, OF MONTREAL, QUEBEC, CANADA, ASSIGNOR TO HARRY STILLSON
HART, OF CHICAGO, ILLINOIS.

DRAFT-RIGGING FOR RAILWAY-CARS.

1,195,942.

Specification of Letters Patent. Patented Aug. 22, 1916.

Application filed January 7, 1911. Serial No. 601,428.

To all whom it may concern:

Be it known that I, WINFIELD H. YOST, a citizen of the United States, residing at Montreal, in the Province of Quebec and Dominion of Canada, have invented certain new and useful Improvements in Draft-Rigging for Railway-Cars, of which the following is a description.

The object of my invention is to provide 10 a draft rigging for railway cars whereby the draw-bar will be yieldingly connected with the draft timbers of the car; the mechanism being such that the application of force will meet with a yielding resistance, and 15 when the force is removed, the recoil will be reduced to a minimum.

A further object of my invention is to provide a lever mechanism which is so constructed as to prevent any displacement of 20 the same during its movement; and which will return to normal position without introducing any unnecessary parts or complications; the lever mechanism being so made that the forces caused through the action 25 of the followers on the levers, and the levers on the springs, and the fulcrum end of the levers on the draft timbers, will be in substantially parallel lines and also parallel to the center line of the car, thus preventing 30 any undue strains or spreading tendency of the center sill of the car; said mechanism also being so constructed that the movement of the levers in relation to each other will be made positive, the draft rigging being simple 35 and efficient in construction, possessing a number of advantages as will more fully appear from the following detailed description.

In the drawings: Figure 1 is a horizontal 40 central sectional view of the draft rigging secured in place, looking downwardly. Fig. 2 is a longitudinal sectional view taken on the line *a—a* of Fig. 1. Fig. 3 is a cross sectional view of the mechanism. Fig. 4 is a transverse sectional view taken on the line 45 *b—b* of Fig. 1, looking in the direction of the arrows, showing the lever mechanism in elevation. Fig. 5 is a perspective view of two of the levers, showing the same before they 50 are assembled or placed on each other. Fig. 6 is a plan view of a modified form of levers; the same being shown assembled in operative relation to each other.

1, 1 are cheek plates or members secured 55 to the draft members 2, 2. The cheek plates

or members are provided with draft lugs 3, 3 and 4, 4 at both ends of the members. These cheek plates or members are preferably provided with a lower flange 5, integral with the cheek plates or members, extending 60 between the lugs 4, 4. This flange is omitted where the fulcrum ends of levers 11 and 12 and followers 13 and 14 bear, to allow for the assembling of the draft gear after the cheek plates with the draft lugs have been 65 secured in place on the car. The upper edges of the plates or members 1, 1 are preferably provided with flanges extending the full length and above the levers and followers, so as to prevent any displacement of the mechanism. A front plate 6 and a rear plate 7 are 70 suitably inserted between the cheek plates with the coil-springs 8 being inserted intermediate of said plates and bearing against them. The springs 8 will hold the plates in 75 yielding engagement with the lever mechanism hereinafter to be described, and form a yielding resistance to the movement of the levers and the draw-bar with relation to the draft timbers. In the construction shown in 80 Fig. 1 where two similar coil-springs 8, 8 are employed, I provide an intermediate bearing plate 8^a against which the adjacent ends of the springs 8^a are secured. A draw-bar 9 which carries the coupler, not shown, is suitably mounted in the car-frame and is provided with a tail strap or yoke 10 which is suitably secured to the draw-bar by rivets or otherwise. Mounted between the plate 6 and the front follower plate 13, and between 85 plate 7 and the rear follower plate 14 are a set of levers consisting of oppositely movable members. I prefer to employ two sets or pairs of levers 11 and 12 at each end of the mechanism, as can more clearly be seen 90 in Figs. 2, 3 and 4. The inner ends of levers 11 are provided with the vertically extending lugs 15, while the levers 12 are provided with the downwardly extending lugs 16, see Fig. 5. The levers 11 and 12 are also provided with the ribs or flanges 17 and 18, respectively, at a point intermediate of the ends of the levers and on the adjacent or contacting surfaces thereof, see Fig. 5.

When the levers are assembled the lugs 105 15 and 16 will bear against the narrower sides of the correlated or adjacent levers, while the ribs or flanges 17 and 18, which are formed in an arc of a circle, abut against each other and control the move- 110

ment of the levers in both directions. The levers are superimposed by bringing the adjacent faces of the two levers, shown in Fig. 5, together, and the ribs or flanges 17 and 18 will prevent any transverse movement of the levers, while the lugs 15 and 16 will cause the levers to interlock at the extreme point of their movement or travel in one direction, and while the levers are at rest or in normal position, the lugs will prevent further movement in the other direction.

In the operation of the draft rigging, as shown in Fig. 1, when force is applied to move the car to the left the tail strap or yoke 10 will move the follower plate 14 and the levers 11 and 12 adjacent thereto bodily toward the left (compressing springs 8) until the outer, or fulcrum, ends of the levers engage the draft lugs 4, the resistance to the movement of the yoke up to this point being only that due to the direct expansive force of the springs. Further movement of the yoke to the left causes the levers to rotate upon the draft lugs 4 as fulcrums, the follower bearing upon the sides of the levers and causing them to rotate and increase the resisting power of the springs by reason of the differential movement between the follower and levers, this differential movement becoming greater as travel increases due to the fact that the convex sides of the levers cause the points of engagement between the latter and the follower to move toward the fulcrum ends of the levers as the latter rotate, as will be readily understood. These parts are preferably so designed that when the limit of compression of the springs is reached (springs solid) the points of engagement of the follower and levers are substantially in longitudinal line with the faces of the draft lugs so that there will be a minimum liability of damage to the levers by the application of a force beyond the elastic capacity of the gear. The faces of the levers which engage the draft lugs are preferably so disposed as to be in flat contact with the latter when the limit of movement is reached in order to increase the bearing area between such faces and the draft lugs.

During the movement of the levers the correlated surfaces 17 and 18 of the respective levers bear against one another and prevent the levers sliding over one another and moving out of engagement with the draft lugs, these surfaces also serving to insure uniform rotation of both levers.

In the event of the springs becoming broken, or of the failure of some part, whereby the travel of the levers will be increased beyond the normal limit, the lugs 15 and 16 will interlock and prevent the levers from rotating sufficiently to disengage from the draft lugs and so obviate total failure of the gear.

During the above described operation the

levers at the other end of the gear remain immovable the pressure of the springs being transmitted directly through the widened inner ends of the levers to the follower and from the latter to the draft lugs 3, the lugs 15 and 16 engaging the faces of the respective levers and preventing any slight oscillation of the fulcrum ends of the levers, holding the latter rigidly interlocked.

It will be apparent that, the divergence of the engaging faces of the levers away from the follower toward their fulcrum ends, not only causes the differential movement of the levers and follower to vary during operation, but also causes the forces transmitted through the follower to the levers to be perpendicular to the bearing face of the follower and parallel to the center line of the car throughout the entire movement of the gear, thus obviating liability of spreading the sills.

As each end of the draft gear is exactly similar in construction the operation of the gear when force is applied in the opposite direction will be readily understood from the above description.

When the force is removed, thereby releasing the gear, lugs 19 formed on the cheek plates, 1, 1, will interfere with the backward movement of the levers should there be any tendency of the latter to bind at the surfaces 17 and 18 and come back bodily instead of rotating. These lugs 19 will insure the return of the levers to their released or normal position; while the ribs 17 and 18, on levers 11 and 12, respectively, or the segmental gears 17^a and 18^a, on levers 11^a and 12^a, respectively, in the modified construction, will guide the levers in their return movement.

A suitable number of carriers 20 are employed,—preferably two in number, as illustrated in Figs. 2, and 3, and 4,—made trough shaped and extending underneath the yoke and across from sill to sill, being fastened to the sill flanges 2^a, as shown in Figs. 3 and 4. These carriers not only form ties for holding the sills or cheek plates at a positive distance apart, but also carry the yoke 10 which in turn carries the entire draft gear. The draft gear is assembled in the following manner:—the yoke 10 is formed as shown in Fig. 2 and connected to coupler 9 with rivets or in any suitable manner, then the followers 13 and 14, levers 11 and 12 and springs 8, front and rear plates 6 and 7 and intermediate bearing plate 8^a, are fitted into the yoke and then moved up or placed in between the cheek plates 1, 1 in proper place between the draft-lugs thereof; the cheek plates having previously been riveted or secured to the center sills 2, 2 of the car. After the mechanism has been thus assembled and put into place, the carriers 20 are bolted to the sills as previously described,

thereby completing the application of the gear or draft rigging to the car.

In the modification illustrated in Fig. 6, the levers 11^a and 12^a are provided with teeth in the form of a segment of a gear, instead of employing the correlated ribs 17 and 18, shown in Fig. 5. The teeth of the different levers are intended to mesh with each other as clearly illustrated in Fig. 6. In addition to the fact that greater friction between the levers is obtained with this construction, the operation or relative movement of the different levers is made more positive by reason of the interlocking or meshing of the teeth. Furthermore, if this construction is employed, should a lever upon one side of the mechanism break, the lever on the opposite side would still operate. In other respects the levers are the same in construction as the levers previously described.

The construction of draft rigging that I have described and illustrated in the drawings may be varied in certain minor details without departing from the spirit of my invention, and I do not wish to be understood therefore as limiting myself to the exact construction illustrated, but

What I claim as my invention and wish to secure by Letters Patent is:—

1. A draft rigging having levers whose ends project beyond the line of the draw-bar with spring-mechanism interposed between them, the levers being provided at a point intermediate of their ends with abutting surfaces to prevent transverse movement of the levers relative to one another.

2. A draft rigging comprising a yoke, levers mounted within said yoke and projecting beyond the sides of the yoke, said levers being provided with correlated surfaces on their adjacent faces whereby transverse movement of the levers relative to one another is prevented, spring mechanism interposed between the levers located at opposite ends of the yoke, and a follower plate arranged intermediate of the levers and the ends of the yoke.

3. A draft rigging having levers projecting laterally beyond the line of the draw-bar with spring-mechanism interposed between them, the levers being provided at a point intermediate of their ends with abutting surfaces arranged to substantially describe the arc of a circle and prevent transverse movement of the levers.

4. A draft rigging comprising cheek plates provided with draft-lugs arranged in pairs at opposite ends of the cheek plates, levers arranged in pairs at opposite ends with their outer ends extending between the draft-lugs, the levers being provided with abutting surfaces intermediate of their ends whereby transverse movement of the levers relative to one another is prevented, spring-

mechanism intermediate of the levers at opposite ends of the cheek plates, and means intermediate of the outer ends of the levers and one of the draft-lugs on each cheek plate whereby the levers will be forced to normal position when pressure on the draft-rigging is released.

5. A draft rigging consisting of levers whose outer ends project beyond the line of the draw-bar with spring mechanism interposed between them, said levers being provided with protruding portions at opposite ends of adjacently arranged levers, said portions having longitudinal bearing surfaces adapted to lock the adjacently arranged levers against relative movement in one direction and interlock when the levers reach a predetermined point in their relative movement in the opposite direction, and means whereby movement of the levers lengthwise of each other is prevented.

6. A draft rigging for cars, comprising cheek plates having a pair of draft-lugs at opposite ends, levers whose outer ends extend beyond the line of the draw-bar and between the draft-lugs at each end, said levers being provided with abutting arcuate surfaces about which the respective levers rotate, whereby relative movement of the levers lengthwise of each other is prevented, said levers being provided with interlocking surfaces whereby independent movement of the levers in either direction beyond predetermined points is prevented, spring mechanism imposed between the levers arranged at opposite ends of said plates, and follower plates arranged intermediate of the levers and the outer draft lugs of each pair.

7. In a draft rigging, spring mechanism, levers, fulcrum members for such levers, the latter in their normal position being out of engagement with the fulcrum members, and abutments adapted to prevent movement of the levers out of the path of the fulcrum members.

8. A draft rigging for cars, having spring mechanism and levers extending across the longitudinal center line of the rigging and adapted to act upon such mechanism, the levers being provided with abutting surfaces to prevent transverse movement relative to one another.

9. In a draft rigging, spring mechanism, followers, loosely mounted levers and fulcrum members for the levers, such levers being interposed between the spring mechanism and followers and normally out of engagement with the fulcrum members.

10. In a draft rigging, spring mechanism, followers, loosely mounted levers and fulcrum members for the levers, such levers being interposed between the spring mechanism and followers and normally out of engagement with the fulcrum members, the inner ends of the levers being engaged.

opposite sides by said followers and spring mechanism when the device is at rest.

11. In a draft rigging, spring mechanism and levers adapted to fulcrum upon the ear and act upon the spring mechanism, each of such levers having a curved surface concentric with the arc described by the lever, the curved surfaces of the levers being adapted to abut.
12. A draft rigging including spring mechanism, levers adapted to rotate and act upon the said mechanism, such levers presenting abutting surfaces to prevent transverse movement of the levers relatively to one another and interlocking means upon the levers to prevent disengagement of the latter one from the other in their rotation.
13. In a draft rigging, draft lugs, spring mechanism, superimposed relief levers each fulcruming upon such lugs at one end, such levers having abutting surfaces adapted to

insure rotative movement of the levers upon such fulcrum during operation, and members upon such levers providing locking means adapted to limit the rotative movement of the levers in the direction to compress the spring mechanism, for the purpose set forth. 25

14. In a draft rigging, draft lugs, spring mechanism, superimposed relief levers each 30 fulcruming upon such lugs at one end, such levers having abutting surfaces adapted to insure rotative movement of the levers upon such fulcrums during operation, and members upon such levers providing locking 35 means adapted to limit the rotative movement of the levers in either direction, for the purpose set forth.
